Michael W. McArdle and Ivar Jeppsson, Chicago, Ill., assignors to Chicago Flexible Shaft Company, Chicago, Ill., a Corporation of Illinois

Application June 5, 1933. Serial No. 48,289

Term of patent 7 years

To all whom it may concern:

Be it known that we, MICHAEL W. MCARDLE, a citizen of the United States, and IVAR JEPSSON, a subject of the King of Sweden, residents of Chicago, in the county of Cook and State of Illinois, have invented a new, original, and ornamental Design for a Combined Slicer and Shredder, of which the following is a specification, reference being had to the accompanying drawings, forming part thereof.

In the drawings—

Figure 1 is a perspective view of a combined slicer and shredder, embodying our new design; Fig. 2 is an end view thereof, and Fig. 3 is a perspective view of the rear side thereof.

We claim:

The ornamental design for a combined slicer and shredder, substantially as shown.

MICHAEL W. MCARDLE.
IVAR JEPSSON.
